(57) **CLAIM**

The ornamental design for an electronic smoking article, as shown and described.

DESCRIPTION

FIG. 1 is a perspective view of an electronic smoking article showing our new design.

FIG. 2 is side elevational view thereof, the other side being a mirror image.

FIG. 3 is an end elevational view thereof; and,

FIG. 4 is a cross-sectional view taken along the line 4-4 shown in FIG. 3.

The broken line showing illustrates portions of the electronic smoking article which form no part of the claimed design.
